UNITED STATES PATENT OFFICE.

HARRY CHRISTENSEN AND EDMOND L. BRUNSWICK, OF CHICAGO, ILLINOIS.

DESIGN FOR A LIGHT STAND.

Application filed February 9, 1922. Serial No. 609. Term of patent 3½ years.

To all whom it may concern:

Be it known that we, HARRY CHRISTENSEN and EDMOND L. BRUNSWICK, citizens of the United States, residing at Chicago, in the county of Cook and State of Illinois, have invented a new, original, and ornamental Design for a Light Stand, of which the following is a specification, reference being had to the accompanying drawings, forming part thereof.

Figures 1 and 2 are, respectively, side and plan elevations of a light stand showing our new design. In Figure 1 of the drawings, one-half of the stand is indicated in outline.

The portion represented by the blank space, however, is ornamented in the same manner as the portion more fully illustrated.

We claim:

The ornamental design for a light stand as shown.

In witness whereof, we hereunto subscribe our names this 23 day of January, 1922.

HARRY CHRISTENSEN,
EDMOND L. BRUNSWICK.
